UNITED STATES PATENT OFFICE.

ERNEST D. MALOY, OF NEW SHARON, IOWA, ASSIGNOR OF ONE-HALF TO DAVID W. CAYLOR, OF NEW SHARON, IOWA.

RADIATOR PROTECTOR.

Application filed February 18, 1922. Serial No. 537,511.

To all whom it may concern:

Be it known that I, ERNEST D. MALOY, a citizen of the United States, and a resident of New Sharon, in the county of Mahaska and State of Iowa, have invented a certain new and useful Radiator Protector, of which the following is a specification.

The object of my invention is to provide a radiator protector or shield of simple, durable and comparatively inexpensive construction.

More particularly my invention relates to a protector or shield for automobile radiators, the protector or shield comprising a single sheet of material formed with shutters, the shutters being capable of swinging movement for permitting air to pass through the radiator. The shutter being formed by cutting a three-sided cut in the sheet of material and scoring a fourth side, whereby, the cut portion and scored portion will define a shutter.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 is a front elevation of a radiator of an automobile with my protector attached thereon.

Figure 2 is an enlarged central sectional view taken through the radiator and protector.

Figure 3 is a detailed sectional view taken on line 3—3 of Figure 1.

Figure 4 is a detailed sectional view of a portion of the protector.

Figure 5 is an enlarged detailed view of a portion of the protector.

Figure 6 is a detailed sectional view taken on the line 6—6 of Figure 5.

Figure 7 shows a modified form of the spring used in closing the shutters of the protector.

In the accompanying drawings, I have used the reference numeral 10 to indicate the shell of a radiator and 11 to indicate the core portion of the radiator. Secured to the core 11 and extended through the shell 10 is the inlet pipe 12.

The hood of the automobile is referred to by the reference numeral 13. A cowl 14

and dash 15 are provided. The parts just described being of ordinary construction.

My invention consists of a flat sheet of material 16 preferably of paper. The sheet of material 16 rests against the core 11 and is held in place by the shell 10, which overlaps the edges of the sheet 16. The sheet 16 is of comparatively thin material so that it may be received beneath the shell 10. The sheet 16 is provided with a number of three-sided cut portions 17.

Connecting the free ends of the cut portions 17 is a scored portion 18. The cut and scored portions 17 and 18 define what I call the shutters of my device. The shutters are referred to by the reference numeral 19. The blades 19 are permitted to swing, the scored portion 18 serving as a hinge.

In this connection it may be mentioned that the scored portion 18 so weakens the sheet of material 16 that it serves as a hinge for permitting swinging movement of the blade 19.

In order to open and close the blades 19, I provide the following described mechanism.

Secured to the sheet 16 below the lowermost shutter 19 is a strip 20, so bent as to form a pair of guides 21 and 22. Each of the guides 21 and 22 is provided with inclined slots 23.

The slots 23 incline upwardly and outwardly. The purpose of the inclined slots 23 will be hereinafter more fully set forth.

Extending into the guides 21 and 22 are the rods 24 and 25. Pins 26 are extended through the rods 24 and 25 and through the slots 23 in the guides 21 and 22.

The upper end of the rods 24 and 25 have fixed to them flexible elements 27 and 28. Extending through the shell 10 and resting on the upper surface of the core 11 of the radiator, is a pair of tubes 29 and 30. The flexible element 27 extends through the tubes 29, while the flexible element 28 extends through the tube 30.

A pair of tubes 31 extend from the dash 15 to the cowl 14 and are fixed in a plate 32. On the plate 32 is a yoke shaped support 32^a in which are pivoted two crank levers 32^b as shown in Figure 6. The flexible wires 28 are extended through the tubes 31 and fastened to the lower ends of the levers 32^b. The other ends of the levers, which serve as handles, have hooks 32^c which engage

notches 32^a in levers 32^c which are pivoted by a pin 32^f in the support 32^a. A spring 32^g encircles the pin 32^f and has its ends received under the arms 32^e for holding them 5 against the hooks 32^c.

It will be seen that when one of the levers is pushed inwardly that the wire attached 10 will be drawn outwardly, thus opening the protector. The arm 32^e will hold the lever in any desired position.

By arranging the tubes 29, 30, and 31, I am able to guide the flexible elements very easily.

Fixed to the lower ends of the rods 24 and 15 25 are the springs 33 and 34. The lower ends of the springs 33 and 34 are anchored to the sheet 16. Fixed to each of the shutters 19 is a yoke member 35. The yoke members 20 extend around the rods 24 and 25 as clearly illustrated in Figure 1 of the drawings. A portion of the yoke devices 35 are secured to the rod 24, and the remainder, to the rod 25.

In Figure 7 I have shown one of the 25 springs in modified form. The spring 34 is fastened to the rod 25 at a point approximately midway of its length, and the guide device is done away with.

The pulling of either of the flexible elements 30 27 and 28 will cause a portion of the shutters 19 to be swung on the scored portion 18. When the rods 24 and 25 are raised 35 they will also be thrown outwardly by the inclined slots 23. The moving of the rods 24 and 25 outwardly, when the shutters are opened is extremely necessary.

If the inclined slots 23 were not provided the springs 33 and 34 would hold the lower ends of the rods against the material 16.

The guides and slots permit the opening 40 of the shutters uniformly. One set of shut-

ters might be opened partially without opening the other set in view of the fact that the rods 24 and 25 are spaced from the shutters 19, as clearly illustrated in Figure 5 of the drawings. Fastening the chain links 32 in 45 the hooks 36 will hold the shutters in their open position against the action of the spring 33 or 34 as the case may be.

As soon as the flexible elements are released the springs will immediately cause the 50 shutters to be moved to closed position.

The advantages of my device are the simple details and the fact that the shutters and backing of the protector member is composed of a single sheet of material. 55

When paper is used the sheet of material is water-proofed so as to stand up whether it is wet or not.

Some changes may be made in the arrangement and construction of the various parts 60 of my device, without departing from the essential features and purposes of my invention, and it is my intention to cover by my claim, any modified forms of structure or use of mechanical equivalents, which may be reasonably included within its scope. 65

I claim as my invention:

A radiator protector of the class described including a flexible sheet member, hinged 70 shutter members formed from said sheet with their upper marginal edge formed integral therewith, said shutter members having a scored line along their upper edge for permitting hinged movement of the shutter members relative to the flexible sheet, a member for connecting the shutters together and for operating them as specified. 75

Des Moines, Iowa, January 31, 1922.

ERNEST D. MALOY.
